SAFETY DEVICE TO PROTECT CARRIER ENTRANCES

Filed Feb. 28, 1924

Inventor.
Charles H. Langs.

Emery, Booth, Janney & Janney. *Attys.*

UNITED STATES PATENT OFFICE.

CHARLES H. LANGS, OF CHICAGO, ILLINOIS.

SAFETY DEVICE TO PROTECT CARRIER ENTRANCES.

Application filed February 28, 1924. Serial No. 695,698.

The object of the present invention is to provide a practicable and reliable means to prevent the starting or running of an elevator, car or other carrier while the entrance thereto is unguarded.

An illustrative embodiment of the invention is shown in the annexed drawings, by reference to which the invention will be readily understood.

10 The construction selected for illustration is described in connection with an electric elevator, typifying any electrically controlled vehicle or carrier to which the invention may be applied.

15 In said drawings:

Fig. 1 is a view looking from the interior of an elevator cage of an installation of means embodying the invention;

20 Fig. 2 is an enlarged sectional view of a circuit closing device appearing at the left-hand side of Fig. 1;

Fig. 3 is a cross section of said device on the line 3-3 of Fig. 2, looking in the direction of the arrows.

25 A door for closing an entrance to a carrier is represented in the illustrative construction by a horizontally sliding elevator well door 1. A portion of the upper part of said door, as viewed from the interior of 30 the elevator cage (not shown) appears in Fig. 1. The doorway is defined in part by the side and upper frame members 2 and 3.

As represented in Fig. 1, the door is in nearly closed position. A jamb against 35 which the door closes is represented by a rubber buffer 4 carried by an abutment bracket 5 on the vertical frame member 2.

The door is shown provided with a spring-actuated latch 6 adapted when the 40 door is closed to engage a catch 7 bracketed to the upper cross member 3. Said latch may be connected by the rod 8 to any appropriate door-operating lever or handle (not shown) by means of which the elevator 45 operator releases the latch as he shifts the door to open position, i. e., toward the right in the specific arrangement selected for illustration.

The operation of the elevator is controlled 50 by an electric circuit sufficiently represented in the drawings by the insulated circuit wires 9 and 10, 11. This circuit may be connected with a controller (not shown) in the elevator cage or car, by which the operator starts, stops and controls the speed 55 of the car in the usual manner.

Connected in said electric circuit is a door-operated circuit-closer comprising relatively movable contact members 12 and 13, one connected by the binding post 14 with a 60 flexible lead or end of the circuit wire 10, and the other connected by a binding post 15 with a flexible lead or end of the circuit wire 11. When the door is closed and latched, these contact members 12 and 13 are 65 maintained in contact with each other as shown in Fig. 2; but when the door is opened said contact members are moved apart or out of contact with each other by a spring 16, thereby opening the electric circuit, as represented in Fig. 1. This will require closing the door before starting the elevator, thus insuring against premature starting or running of the elevator while the door remains open.

75 The contact members 12 and 13, one of which is linearly movable under the impulse of the door in closing, are formed with broad contact surfaces inclined to the line of said movement and adapted to slide one 80 against the other with a transverse pressure or thrust, on the principle of a wedging or inclined plane action, as will be readily understood from the drawings. As specifically represented, the contact member 13, 85 being the member impelled by the door, moves under and lifts the contact member 12 by sliding engagement therewith, said member 12 being arranged to bear yieldingly on the lower member 13.

90 Contacts of the character indicated insure a positive contact of the contact members when moved into coacting relationship, with substantial areas of contact surfaces, and maintain such contact during a considerable 95 range of relative movement of said members, thereby allowing for variations in the closing movements of the door, or of different doors to which devices embodying the invention may be applied. Moreover they 100 entail a self-cleaning and polishing of the contact surfaces by their frictional sliding engagement, thus maintaining them free of dust or other foreign matter or of such effects of corrosion as to impair their efficiency. 105 It will be understood that the contact members may be of any appropriate conducting material, preferably brass.

The upper contact member 12 is represented in the form of a pivoted arm or lever 110 having an enlarged weighted head which bears on the lower contact member. Thus

the weight of said head may be utilized in lieu of springs or the like to maintain the positive pressure of the contact members one against the other during their coaction.

5 This arrangement is both simple and effective.

An insulated pivot stud for the upper contact member is indicated at 17. Another insulated stud for limiting the downward movement of said upper contact member, before its engagement by the lower contact member 13, is indicated at 18. These may be metallic studs enclosed by insulating bushings or sleeves. The insulating bushing 15 for the pivot stud 17 may advantageously be pressed in the fulcrum sleeve 19 of the upper contact member.

The contact member 13 is carried by a plunger rod 20 which is operated by the door in a direction to move said member into engagement with the member 12, and is impelled in the opposite direction by the spring 16. Said rod 20 is slidably mounted in appropriate bearings 21, preferably of insulating material. The forward portion of the rod is shown of square or polygonal formation, and slides in a correspondingly formed bore in its bearing, thereby preventing rotation or turning of the rod. A shoulder 22 is provided by the juncture of the round and square portions of the rod. Non-rotatably fitted on this shouldered portion of the rod is an insulating block 23 carrying said contact member 13 which is saddle-shaped to straddle said insulating block, as shown in Fig. 3 and is secured thereto by the screw 15, which screw is utilized as the binding post for connecting the contact member with the circuit wire 11. 40 The spring 16, shown as a coil spring enclosing the plunger rod, and insulated therefrom by an insulating bushing or sleeve 24, bears against the insulating block 23, which by virtue of the shoulder 22 forces the plunger rod toward the door under the impulse of said spring. A screw 20^a holds the insulating block 23, rod 20 and insulating sleeve 24 in proper relationship. By this simple construction and arrangement, the 45 parts may be conveniently assembled in operative relationship and the contact member 13 is thoroughly insulated from the operating parts.

As represented in the drawings, the plunger rod 20 is horizontally disposed and projects beyond the door abutment or buffer 4 directly in line with the door, so that the movement of the contact member 13 into engagement with the coacting member 12 is effected by the direct thrust of the door in its closing movement on the plunger rod, against the compression of the spring 16. By this arrangement, the action of the spring will serve to force back the door if 60 it fails to latch, so that, even though the door

in closing may have effected a momentary closing of the electric circuit, the circuit will be immediately opened by movement of the parts to the relationship shown in Fig. 1, thus shutting off the power and stopping the elevator.

From the foregoing description, it will be seen that a practicable and reliable means is provided to compel the operators of elevators or other carriers to comply with a safety ordinance designed to protect human life, namely the requirement of closing and latching the doors guarding the entrances to such carriers before starting the carriers in movement. The circuit closer automatically opens the operating circuit for the carrier when the door opens and, with the specific construction shown, impels the opening of the door from closed position sufficiently to open the circuit if the door is unlatched. On the other hand, the closing of the circuit when the door closes is independent of the degree of pressure of the door against its abutment, and a positive bearing contact, with substantial area of contact surfaces, is maintained during a considerable range in the closing movement of the door, insuring reliability of operation and yet allowing for variations in practice. In other words, the construction of the circuit closer is such as to require no nicety of adjustment to arrange it in proper operative relation to the door. Moreover the contact members automatically maintain their contact surfaces clean and bright, insuring efficient operation after prolonged service. The construction of the circuit closing appliance is also of simple and practicable character, and susceptible of economical manufacture.

The elements composing the circuit closing appliance may be mounted and housed in an appropriate box 25, which may be supported by attachment to a suitable fixture to maintain the plunger rod 20 in proper relation to the door. In this instance said box is shown attached to the abutment bracket 5. Conduits 26 for the electric circuit wires are shown entering the top and bottom of the box and secured thereto by nuts 27. The bearings 21 for the plunger rod 20 are shown as flanged sleeves projected through openings in the side walls of the box and secured thereto by nuts 28.

For economy of manufacture the box 25 may be constructed as a metal casting or stamped from sheet metal. It is shown having a hinged lid 29, the lid being represented as raised in Fig. 1 and as closed in Fig. 3. The lid may if desired be fastened by appropriate fastening means engaging holes in the lower extremity of the lid and a flange 30 projecting from the bottom of the box.

In the illustrative construction, the parts composing the circuit-closing appliance are arranged and operate in the same vertical

plane, which among other advantages permits them to be housed in a very shallow or narrow box.

Obviously the present invention is not limited to the precise construction and arrangement shown in the drawings, since the details of construction, arrangement and operation may be variously modified to suit various requirements and conditions. Moreover it is not indispensable that all of the features of the invention be used conjointly since they may be advantageously used in various different combinations and sub-combinations.

Having thus described an illustrative embodiment of my invention, I claim:

1. A device of the class described comprising, in combination, relatively movable contact members adapted for connection in an electric circuit for controlling the operation of a carrier; said members having contact surfaces inclined to the direction of their relative movement and adapted for coaction by sliding engagement of said surfaces; one said members adapted to bear yieldingly against the other during such engagement; a stop for limiting the movement of said last named member prior to such engagement; resilient means for moving said members out of contact; and door-operable means for moving said members into sliding contact.

2. A device of the class described comprising, in combination, a linearly movable contact member having an inclined contact surface; a coacting weighted contact member having a correspondingly inclined contact surface and adapted to bear by gravity upon said first named member and thereby maintain an equal pressure of contact therewith during sliding engagement of said contact surfaces; a door-operable means for moving said linearly movable member into sliding contact with said weighted member; and means opposing said movement and adapted to maintain said members out of contact when said door-operable means is released.

3. A device of the class described comprising,

ing, in combination, a spring-impelled rod adapted to be forced in opposition to its spring by the closing of a door; bearings in which said rod is slidably fitted; said rod having cylindrical and polygonal portions fitted in the respective bearings, and a shoulder at the juncture of said portions; an insulating block fitted on the shouldered portion of said rod; a rod impelling spring bearing against said block; a contact member carried by said block; and a coacting contact member; said members having contact surfaces inclined to the line of movement of said rod.

4. A device of the class described comprising, in combination, a spring-impelled slideable rod adapted to be forced in opposition to its spring by the closing of a door; a contact member carried by said rod having an inclined contact surface; and a coacting contact member comprising a pivoted arm having an enlarged head provided with a correspondingly inclined contact surface and adapted to bear by gravity upon said first named member and thereby maintain an equal pressure of contact therewith during sliding engagement of said contact surfaces.

5. A device of the class described comprising, in combination, a slideable rod adapted to be actuated by the closing of a door; insulating bearings in which said rod is slidably mounted; an insulating block secured on said rod; a coil spring enclosing said rod and interposed between one of said bearings and said insulating block to oppose the actuation of the rod by the door; an insulating bushing fitted on said rod within said spring; a contact member carried by said insulating block; and a coacting contact member yieldingly bearing on the first mentioned member; said contact members having contact surfaces inclined to the line of movement of said rod.

In testimony whereof, I have signed my name to this specification.

CHARLES H. LANGS.
